United States Patent Office

Des. 179,170

Patented Nov. 6, 1956

179,170

AUTOMATIC POPCORN MACHINE

Samuel M. Waas, Kansas City, Mo., assignor to Manley,
Inc., Kansas City, Mo., a corporation of Missouri

Application March 26, 1956, Serial No. 40,780

Term of patent 14 years

(Cl. D81—10)

Fig. 1.

Fig. 2.

Figure 1 is a front perspective view of an automatic popcorn machine, showing my new design; and

Fig. 2 is a rear perspective view of the automatic popcorn machine.

I claim:

The ornamental design for an automatic popcorn machine, as shown.

References Cited in the file of this patent

UNITED STATES PATENTS

D. 164,267	Waas -----	Aug. 14, 1951
D. 168,814	Waas -----	Feb. 10, 1953
D. 177,161	Waas -----	Mar. 13, 1956